UNITED STATES PATENT OFFICE

DAVID PELTON MOORE, OF AVON PARK, FLORIDA

MEANS FOR AND METHOD OF SECURING MORTISE AND TENON JOINTS

Application filed January 25, 1930. Serial No. 423,451.

The present invention relates to improvements in means for and methods of securing mortise and tenon joints, one object of the invention being the provision of a metallic device provided with means to cooperate both with a slot in the tenon and the walls at the base of the mortise whereby as the tenon is forced into the mortise the device is operated and set in place to in turn attach the tenon both by itself being a fastener and by causing the end of the tenon to be expanded and thus be wedged into the mortise.

Another object of this invention is the provision of a device adapted to enter a slot formed in the end of the tenon as the tenon is being forced in the mortise, such action forcing a prong terminal carried by the device transversely of the mortise to pierce the wall thereof at its base, while spreading the slotted end of the tenon to provide a double acting locking and attaching device for such joint, and rendering the use of an adhesive unnecessary.

Several devices have heretofore been designed for attaching the tenon to the mortise, but they have been unsatisfactory for when they were attached to the exterior of the tenon, no wedging action took place, and when they acted as a wedging device the base of the wall of the mortise was not engaged in a practical manner. This device overcomes these objections by providing in one metallic member a tenon wedging device, which while effecting the wedging action, it itself acted upon to drive one or more prongs into the walls at the base of the mortise.

In order to properly understand the present invention attention is invited to the accompanying drawings, in which have been illustrated several of a number of different designs of devices for accomplishing the results above set forth, and in which:—

Figure 1 is a side elevation of one form of device per se.

Figure 2 is a bottom plan view thereof.

Figure 3 is a detached plan and sectional view of a mortise and tenon joint separated with the present device inserted in the slot of the tenon and just previous to the joining of the members.

Figure 4 is a similar view to Figure 3 of the joint completed with the device in attaching and holding position.

Figure 5 is a plan view of the metal blank of device before bending.

Figures 6, 7, 8 and 9 are views of modified forms of devices, all of which embody the same principles.

Referring to the drawings, and more particularly to Figures 1 through 5, 10 designates the mortise carrying member and may be taken as indicative of a chair frame, rocker or other piece of furniture, in which a usual socket 11 is provided. A tenon 12, here shown as a chair rung, is provided with a slot 13.

The wedging and attaching device 14 here shown as a member stamped from sheet metal, preferably rather stiff sheet steel or iron, is bent centrally as at 15 to provide the relatively flat slot entering portion 16, and the two diverging portions 17 and 18, which cause the device at this portion in plan view to be a modified V or Y, the terminals 19 and 20, being of lesser width than their respective carrying portion and being bent toward each other but in parallel, so that when the device is not in use the extreme ends 21 and 22 of the terminals are nearly within the extreme base edges of the triangle, and slightly below the respective opposite cut-away or guiding edges of the portions 17 and 18. The terminals 19 and 20 being in substantially the same plane and provide a base to rest upon and to contact firmly the base of the mortise when connecting the mortise and tenon joint. Where so desired each portion 17 or 18 may be provided with a short piercing tooth or prong 23, which is normally housed within the space between the portions 17 and 18, and aligned when the portions are compressed together so as to pass through the opening 24 formed in the opposite portions, or as shown the tooth is formed from the portion 17 and the opening in the portion 18.

If desirable, a tooth and opening may be carried by both portions, thus providing oppositely projecting teeth when the portions 17 and 18 are compressed together.

To use the device, the portion 16 is first

inserted in the end of the slot 13 of the rung, and the rung then is inserted with the device so that the terminals 19 and 20 rest upon the base of the mortise or socket. The rung is now forced into the socket, the portions 17 and 18 entering the slot 13 and causing the two terminals to have imparted thereto straight line movement parallel with the base of the socket, their ends 21 and 22 being prevented from rising by the cutaway edges of such portions 17 and 18 and entering the walls of the socket at the base upon opposite sides, so that when the rung is fully seated, the parts will assume the position as shown in Figure 4. As the portions 17 and 18 were entering the slot 13, the wedging action of these within the slot caused the end of the rung to be slightly spread so that the walls of the rung were forced frictionally against the walls of the socket and thus a double fastener was provided. Also as the portions 17 and 18 were being brought together within the slot 13, the tooth or teeth 23 were caused to bite into the material of the rung and thus more securely fastened the device in the rung.

In Figure 6, a slightly modified form is shown, and in which only one piercing terminal is provided, the device being otherwise exactly like that shown in Figure 1, and similar parts being designated by prime indications.

In Figure 7, the portion 17" is shorter and is provided with a tooth 23" upon its end for entering the opening 24".

In Figure 8, the portions 17"" and 18"", each carry respectively a tooth 23"" and circular opening 24"", while in Figure 9, the device is made of a single piece of wire, bent primarily U-staple shaped, and then formed to provide the slot entering short U-shaped portion 25, the two outwardly bent portions 26 and 27, and the inwardly bent and parallel piercing terminals 28 and 29.

In all of these examples, the same action takes place when the rung is forced into its socket, and a joint is formed that makes the use of an adhesive unnecessary and one which is not affected by the climate, and one which will hold fast under all conditions.

What is claimed as new, is:—

1. The herein described method of attaching a tenon in a mortise, which consists in placing a locking and wedging device adjacent the slotted end of a tenon and pressing the tenon into the mortise to compress a part of the device within the slotted end and cause the device to project outwardly at right angles to the base of the mortise and to the walls of the mortise into piercing relation one or more prongs, so that said prongs pierce the walls of the mortise at its base while the wedging portion thereof spreads the end of the tenon into wedging relation to the mortise.

2. A fastener for mortise and tenon joints, including a metallic member provided with two angularly spaced portions, one of which is provided with a piercing terminal disposed to project toward the other spaced portion and be forced below the other spaced portion and into the wall of the mortise when the angularly spaced portions are moved toward each other. 70

3. A fastener according to claim 2, in which the piercing terminal is formed at an angle to its angularly spaced portion and has its extreme end normally adjacent to and below the lower edge of the other angularly spaced portion. 75

4. A fastener according to claim 2, in which the piercing terminals lie approximately side by side in the same plane. 80

5. A fastener according to claim 2, in which one of the angularly spaced portions is provided with an incised short piercing tooth while the other portion is provided with an aperture through which said tooth protrudes when said angularly spaced portions are parallel. 85

6. A fastener made from a single piece of metal and bent substantially Y-shaped in side elevation, the terminals of the head of the Y being bent inwardly and pointed to provide oppositely extending piercing ends, 95 whereby when the reduced portion of the Y is inserted into the slotted end of a tenon and the tenon and fastener are inserted and forced within a mortise the spaced sides of the Y are compressed within the slot of the tenon and the piercing ends are projected into opposite walls at the base of the mortise. 100

7. A mortise and tenon joint attaching device including a strip of metal bent substantially tri-angular in side elevation and having a terminal pointed and bent inwardly to form a portion of the base of the triangle, whereby when the apex of the triangle is inserted in a slot in the end of a tenon and the tenon and device are forced into a mortise the sides of the triangle are compressed by the walls of the slot to cause the pointed terminal to pierce the wall of the mortise at the base thereof and in a plane with the base of the mortise. 110

8. A mortise and tenon joint attaching device, including a strip of metal bent substantially tri-angular in side elevation, the base of the triangle being formed by two oppositely projecting piercing points, lying side by side and adapted when the sides of the triangle are compressed to project in opposite directions and be disposed below the respective aligned portions of the sides, which portions act as a guiding means to prevent any tendency of the points to rise during such projecting movement. 120

In testimony whereof I affix my signature.

DAVID PELTON MOORE.
